UNITED STATES PATENT OFFICE.

JAKOB S. NEUMANN, OF GREAT FALLS, MONTANA.

SAFETY ATTACHMENT FOR VESSELS.

1,129,895.

Specification of Letters Patent.

Patented Mar. 2, 1915.

Application filed May 6, 1913. Serial No. 765,803.

To all whom it may concern:

Be it known that I, JAKOB S. NEUMANN, citizen of the United States, residing at Great Falls, in the county of Cascade and State of Montana, have invented certain new and useful Improvements in Safety Attachments for Vessels, of which the following is a specification.

This invention relates to an attachment in the nature of a buffer or guard, adapted to be used in connection with boats, vessels and ships of various character.

The primary object of the invention contemplates the provision of a cushion attachment in the form of a buffer or guard adapted to be secured to the bow of the boat, to absorb the shock, in the event of a collision, that would ordinarily be received by the boat itself, thereby reducing the ultimate danger as well as the danger attending such a collision.

Another object of the invention resides in the provision of suitable means arranged upon the attachment, and comprising a part of the invention, whereby the direction of travel, in the event of a collision, may be varied or changed, this arrangement preventing a headlong collision and causing the colliding boat to deliver only a glancing blow, thus materially reducing the likelihood of disaster, occurring by reason of the inability of the colliding boat to vary its course or direction of travel.

A still further object of the invention is to provide novel and peculiar means including a plurality of specially arranged springs, whereby two moving boats may collide, or a boat collide with an immovable or floating object, without endangering or wrecking such boat or boats.

The above and additional objects are accomplished by such means as are illustrated in their preferred embodiment in the accompanying drawings, described in the following specification and then more particularly pointed out in the claims which are appended hereto and form a part of this application.

In describing my invention in detail reference will be had to the accompanying drawings wherein like characters denote like or corresponding parts throughout the several views, and in which:—

Figure 1 is a top plan view of a buffer attachment constructed in accordance with

my invention; and Fig. 2 is a side elevation of the attachment.

Proceeding now to the description of the drawings, wherein is illustrated the preferred form of my invention the numeral 1 designates a substantially V-shaped metallic plate adapted to be secured in any suitable manner across the bow of a boat, the said plate having a plurality of projections 2 formed integrally with and struck-out from one face thereof for fixedly connecting a plurality of helical springs 3 varying in size, according to their position with respect to the said plate. The extremities of the V-shaped plate extend outwardly as at 4 and terminate in a vertically extending rod or shaft 5 upon which rollers 6 are disposed, the said rollers being loosely mounted upon the said shaft to allow a free rotation of the rollers should occasion demand.

Any number of springs may be employed in connection with this invention, however in the preferred form five main springs 6 are provided, the said springs being connected to the outer converged end of the V-shaped plate 1 from which point they extend in parallel spaced relation, one spring directly beneath the other. The opposite end of each spring is secured to the inner converged end of a second or forward metallic V-shaped plate 8, the said plate 8 likewise being provided with a plurality of projections 9 formed in alinement with the projections 2 of the plate 1. The terminals of the springs 6 are fastened to the plates 1 and 8 in any suitable manner. Upon each side of the main springs 6 I provide a similar number of springs 10 somewhat smaller than the main springs 6 and secured thereto at various points throughout the length of the springs through the medium of a plurality of twisted wire connections 11. The said springs 10 are secured at each end to the plates 1 and 8 by means of the projections 2 and 9 respectively formed thereupon. Additional springs 12, yet smaller than the springs 10 are provided and disposed in parallel relation upon each side of the intermediate springs 10, the said springs 12 likewise being connected at various points throughout their length to the intermediate springs 10 by means of similar twisted wire connections 13, and secured to the projections 2 and 9 formed upon the plates 1 and 8 of the device. To the extremities of the

forward plate 8, rods 14 are secured, the said rods adapted to have mounted thereupon a plurality of vertically extending rollers 15, the purpose of which will subsequently appear. The converged end of the plate member 8 is provided with rollers 13', the said rollers being journaled within suitable brackets 14' secured to the plate and projecting forwardly therefrom, this arrangement of the rollers preventing a direct blow being struck by the colliding vessel and forcing or sheering either the vessel or the object collided with to one side.

By securely fastening the plate 1 over the bow of a boat, it will be seen that the plate 8 is held in spaced relation thereto by means of the several springs embodied in the invention.

Should the boat upon which the plate 1 is attached collide with either a moving or stationary object it will be seen that the plate 8, by reason of its position, will first engage the said object, in which event the shock created by the collision of the boat 25 and the object is entirely absorbed by the springs comprising the invention. Should a glancing blow be struck, it will be seen that the rollers 15 and 6 will cause the boat to change its direction of travel and allow 30 the same to move unobstructed along side of the object causing the collision.

From the above, taken in connection with the accompanying drawings, it will be seen that the manner in which the springs 3 are disposed and arranged is such as to bring the main springs at the point where the greatest strain is brought to bear upon the device in the event of a collision; and that the provision of the several rollers employed in connection with the invention will obviate to a great extent the many disasters occurring by reason of the inability of the colliding vessel to change its course or direction of travel.

In reduction to practice, I have found that the form of my invention, illustrated in the drawings, and referred to in the above description, as the preferred embodiment is the most efficient and practical; yet realizing that the conditions concurrent with the adoption of my device will necessarily vary to some extent, I desire to emphasize the fact that various minor changes in the details of construction, proportion and arrangement of parts may be resorted to, when required, without sacrificing any of the advantages derived from my invention as defined in the appended claims.

Having thus fully described my invention, what I claim as new and desire to secure by Letters Patent, is:—

1. A buffer attachment for vessels including a plurality of springs, plates to which the springs are secured, one of said plates being supported by the said springs and the

other connected to the vessel, the said springs varying in size, the larger springs engaging the plates centrally, and the smaller springs at each side thereof to receive proportionately the strain exerted upon the plates when colliding.

2. A buffer attachment for vessels including a pair of plates, springs arranged between the said plates, said springs being arranged in series, the springs of each series varying in size, and means connecting the springs of each series to maintain said springs in parallel relation, as and for the purpose set forth.

3. A buffer attachment for vessels including a plurality of serially arranged springs, the springs of each series varying in size from the outer to the centrally disposed springs, plates to which the springs are secured, one of said plates being supported by said springs and the other connected to the vessel, the larger springs engaging the plates centrally, and the smaller springs at each side thereof to receive proportionately the strain exerted upon the said plates during a collision of the vessel with a second object.

4. A buffer attachment for vessels including a pair of plate members, springs interposed between the said plate members, rollers mounted upon the extremities of the said plate members, and means connecting the said springs to maintain the same in parallel relation, as and for the purpose set forth.

5. A buffer attachment for vessels including a pair of substantially V-shaped plate members, a plurality of springs interposed between the said plate members, the said springs being so arranged between the said plate members as to receive proportionately, according to their size, the strain exerted upon the said plates by a collision of the vessel with an object, means supported by the said plates and disposed in the path of the object collided with to veer to one side either the said object or the said vessel, and means connecting the springs to maintain the same in parallel relation, as and for the purpose set forth.

6. A buffer attachment for vessels including a substantially V-shaped plate adapted to be secured upon the bow of a vessel, rollers loosely mounted upon rods carried by the said plate, a second V-shaped plate held in spaced relation to the said first mentioned plate, rollers loosely mounted upon rods formed upon the extremities of the said second mentioned plate, and means including a plurality of springs arranged between the said two plates for supporting the second mentioned plate.

7. A buffer attachment including a substantially V-shaped plate adapted to be secured upon the bow of a vessel, a plurality of projections formed integrally with the

said plate, a plurality of helical springs secured to the said projections, the said springs being arranged in parallel relation to each other, a second substantially V-shaped plate 5 supported in spaced relation to the said first mentioned plate, the opposite ends of the said springs being secured to the said second mentioned plate, and means including a plurality of rollers carried upon the extremi-

ties of each of the said plates, as and for 10 the purpose set forth.

In testimony whereof I affix my signature in presence of two witnesses.

JAKOB S. NEUMANN.
